APPARATUS FOR PUNCHING TUYÈRES OF COPPER CONVERTERS AND THE LIKE

Leonard Larson and Byron T. Berge, McGill, Nev., assignors to Kennecott Copper Corporation, New York, N. Y., a corporation of New York

Application October 1, 1945, Serial No. 619,588

8 Claims. (Cl. 266—42)

1

This application relates to power-driven means for punching the tuyère openings provided in conventional copper-converters, and the like, and pertains particularly to a detachable mechanical puncher device adapted to be secured to the shell of such a converter. One of the particular objects of the invention is to provide a device for performing the punching operation with a high degree of reliability over long periods of use, and at a low cost for service and maintenance.

In the production of blister copper in a smelting plant it is necessary to treat the copper matte which is produced in the reverberatory furnace to remove the impurities, consisting mainly of iron and sulphur. This final step in the production of blister copper is carried out in what is known as a converter, the material under treatment being maintained in molten condition, and the air is introduced to the molten mass through a plurality of openings which are submerged below the level of the molten mass in the converter. During the introduction of this air at these submerged openings, which are termed "tuyères," it is necessary to "punch" the tuyère openings at rather frequent intervals in order to prevent obstruction by the accumulation or growth of slag and the like at the discharge end of the tuyères. Numerous forms of apparatus have heretofore been proposed for the mechanical punching of these tuyères during the converter cycle, but the effectiveness of the hitherto proposed forms of mechanical punching devices has been rather unsatisfactory, and so far as is known, the principal proportion of blister copper is now produced solely by utilizing hand punching methods to keep the tuyères open.

The hand punching operation is commonly considered to be very laborious and disagreeable. Each converter is equipped with a large number of closely spaced tuyères, as an example, there may be about forty-five tuyères horizontally aligned and spaced about six inches apart along the length of the converter at one side. Under ordinary operating conditions it is necessary to punch through each tuyère every few minutes or more as required in order to clear the tuyère pipe outlet. During this hand punching, blowing air is wasted through the aperture through which the hand punch rod is inserted in the tuyère and quite frequently when the punch rod is withdrawn after a punching operation this outward blast of air around the punch rod sweeps away adhering particles of hot slag and forces the same against the man who is doing the punching.

2

In addition to the danger of being burned by the slag which is blown against him, difficulties are introduced by the not infrequent occasions when a punch rod sticks in a tuyère opening, both on the inward stroke and on the outward stroke, causing delays in the punching operation while the stuck punch rod is being freed. The man who is punching stands in front of the tuyère assembly and as he proceeds with the punching operation, he must withstand the air blast and sparks of freed slag material above described. The puncher attempts to complete each punching stroke as rapidly as possible and attempts to break off the accretion without allowing the tip of his punch rod to penetrate too far into the molten bath. He also withdraws the punch rod as quickly as possible to avoid overheating and burning the end of the rod. However, even the most experienced and adept of punchers is unable to regulate with any consistency the distance the rod penetrates into the molten bath and it is difficult for him to withdraw the rod quickly enough to avoid overheating and deformation of the rod.

25 Any device for mechanically punching the tuyères of a converter of the type used in copper smelting must maintain the desirable features obtainable by hand punching, and must in addition, we have determined, meet the following specific requirements:

(1) Provision must be made for individual mountings of separate mechanical punching devices at the position of each tuyère in a converter, rather than a multiple punching construction as has heretofore been suggested in the art, in view of the fact that it is necessary, periodically, to renew the refractory lining of the converting vessel because it is fluxed away during the blowing period in the converting operation, and whenever a new lining is installed and the tuyère pipes are disposed along a predetermined angle so as to dispose the inner ends of the tuyère tubes as nearly as possible along a given level, difficulty is encountered in alining the plurality of tuyère openings at the periphery of the converting vessel because of the uneven expansion and movement which has occurred in the shell structure during the operation period, resulting in warping and distortion. Misalignment of tuyère mountings takes place both vertically and horizontally, and this results in an uneven location of the various tuyère openings at the periphery or shell portion of the converter. Furthermore, the uneven heating and consequent distortion which results during the converter operation necessitates

the provision of individual puncher mechanisms at the individual tuyère openings.

(2) Any mechanical punching device must be very quickly attachable to and detachable from the blowing air supply housing which forms a part of the converter so that in the event a punching device becomes inoperative or otherwise inadequate such device may quickly be removed from the converter and hand punching resorted to. Furthermore, the air supply housing which remains attached to the converter at the position of a tuyère should be of such character as to permit normal hand punching of that particular tuyère immediately upon withdrawal or disattachment of the mechanical punching device.

(3) Means must be provided for the complete support of the mechanical puncher upon the converter when in use thereon, independent of any outside structure so that, in effect, the mechanical puncher when mounted upon the converter will actually become a part of the converter and will move integrally therewith.

(4) A mechanical puncher must be arranged for attachment to the converter, in cooperation with the air supply housing which forms a part of the converter, in such manner as to prevent loss of blowing air, while at the same time carrying the mechanism (punch rod, sleeve and forward end of piston rod) which does the actual punching within the tuyère in a freely supported condition independent of the air supply housing, for free reciprocating motion within the tuyère tube.

(5) Suitable means must be provided for alignment of the punching mechanism and the accompanying punch rod which is disposed within the tuyère tube upon the blowing air supply housing, in such manner that the punch rod is substantially aligned with the tuyère openings, for free operation at various angular positions of the converter.

(6) The mounting for the punch rod should be such that a pronounced "whipping" action is secured at the inner end of the punch rod during the punching operation, so that the free end of the rod will have a tendency to shake off adhering slag or metallic material, and thus, inhibit accumulation upon the rod, and also have a tendency to punch an opening through the tuyère accretion which is somewhat larger than the punch rod itself.

(7) The combination must provide for a supply of blowing air through the tuyère tube and the punched opening at the inner end of the tuyère tube when the tip of the punch rod has been passed through the obstruction zone at such inner end, in a punching operation, so that blowing air is substantially continuously introduced to the interior of the converter around the tip portion of the punching rod as it is returned through the obstruction zone in the completion of a punching stroke.

(8) The mechanical driving member for the punch rod should be such as to drive the punch rod forwardly under a high force until the tip of the punch rod has passed through the obstruction zone, and to thereafter quickly stop the forward motion of the punch rod and quickly reverse its direction of movement to withdraw the rod from the molten bath rearwardly past the obstruction zone, while positively limiting the extent of penetration of the tip portion of the punch rod past such obstruction zone into the molten bath.

It is a particular object of this invention to pro-

vide a device which will meet all of the above enumerated requirements.

A further object is to provide a device of the character described, carrying a punch rod normally disposed within the tuyère when the device is attached to the converter shell, but in a withdrawn position with respect to the inner end of the tuyère, in position to be continuously cooled by the blowing air which is supplied to such tuyère.

5 A further object of the invention is to provide a device of the character set forth immediately above and including fluid-operated reciprocating motor means adapted to establish a forward and 15 rearward reciprocatory motion of an associated punch rod which is disposed within the tuyère, such a reciprocating motor means being provided with means normally causing the punch rod to occupy a rearward or withdrawn position with respect to the inner end of the tuyère.

20 A further and specific object of the invention is to provide a detachable tuyère punching device, together with an air supply housing member permanently secured to the converter and adapted to 25 receive and support the punching device, such housing member being provided with a valve member adapted to prevent egress of blowing air from the housing member upon detachment of the punching device, together with support means 30 provided on the punching device adapted to engage such valve member and maintain the same out of contact with the reciprocable punch rod associated with such punching device when such punching device is attached to the housing member in use.

35 The above and other objects of this invention will be brought out in more particularity in the accompanying description of a certain preferred embodiment thereof, or will be apparent from 40 such description. This preferred embodiment is illustrated in the accompanying drawings, in which:

45 Fig. 1 is a partly broken away side elevation of a copper converter, provided with mechanical punching devices according to this invention;

Fig. 2 is a partly broken-away end elevation thereof, as taken on line 2—2 in Fig. 1;

Fig. 3 is a sectional detail through the converter shell and through one of the punching devices, as taken on line 3—3 in Fig. 1;

Fig. 4 is a view generally corresponding to Fig. 3, but showing the punching device in elevation, on a reduced scale as compared with Fig. 3;

Fig. 5 is a longitudinal section through the 55 mechanical punching device per se, as it would appear when removed from the converter;

Fig. 6 is a transverse sectional view thereof as taken on line 6—6 in Fig. 3;

Fig. 7 is a plan view of the device of Fig. 5;

Fig. 8 is a front view of the air supply housing portion of the construction, as taken on line 8—8 in Fig. 3, but with the puncher device removed from the air supply housing;

Fig. 9 is a transverse sectional view of the 65 structure of Fig. 8, as taken on line 9—9 therein;

Fig. 10 is a view corresponding to Fig. 5, showing a modified form of mechanical punching device adapted to effect positive return of the punching rod upon completion of the forward stroke, independent of the skill of the operator;

Fig. 11 is a front elevation as taken on line 11—11 in Fig. 10;

Fig. 12 is a fragmentary vertical section as taken on line 12—12 in Fig. 10; and

75 Figs. 13 through 15 are fragmentary longi-

tudinal sections, all as taken on line 13-13 in Fig. 12, showing certain relatively movable parts in alternative operative positions.

Referring to the drawings, a copper converter is indicated at 1, provided with supporting rings (or riding rings, as they are termed) as at 2, which ride on rollers 3 carried by base members 4. A fume hood is provided as at 4a for exhaust of the sulphurous fumes which are formed during the converter operation, and a shield member is provided as at 4b to protect the men engaged in the punching operation from the splash of slag or the like from the discharge opening. A cooperating shield member 4c is preferably provided, mounted upon the converter 1 in position to engage the shield 4b in the normal operating position of the converter. The converter 1 comprises a shell 5 of metal, and a refractory lining 6. An opening 7 is provided in the wall of the converter, through which the converter is charged with matte, fluxes and the like, and through which the molten slag and the end product (blister copper) may be discharged upon rotation of the converter clockwise from the position of Fig. 2.

Along one side of the converter a bustle pipe 8 is provided for supply of blowing air to the tuyères, individual flexible connectors 9 being provided from the bustle pipe 8 to the air-supply housings 10 which communicate with the tuyère openings. A radially extending connector 11 is usually provided between the bustle pipe 8 and an axially arranged blowing air inlet pipe 12, so that air may be supplied to the tuyères at all rotative positions of the converter.

For the purposes of this invention, a high pressure air supply line is provided as at 13, preferably running alongside the bustle pipe 8, together with flexible connectors 14 and couplings 14a which connect the high pressure air supply to the tuyère punchers 15 provided for each of the tuyère openings. The housings 10 are attached to the shell 5 of the converter through flanges 16 and bolts 17, and the shell 5 is provided with an opening at the position of each housing 10, as at 18, to receive a tuyère pipe or tube 19 extending through an opening 20 in the refractory lining 6 and leading to the interior of the converter. A passage 21 is defined by the housing 10 to provide blowing air communication from the bustle-pipe connectors 9 to the tuyère pipe 19.

The respective housings 10 are arranged not only to supply low pressure blowing air to the tuyères, but are adapted also to receive the mechanical punching device 15, and means are provided for preventing egress of low pressure blowing air from the space 21 when the puncher 15 is attached to or detached from the housing 10. The housings 10 are each provided with a puncher-receiving opening 22, as defined by a valve seat member 23. A positioning pin 24 is arranged to engage a recess or slot 25 in the rim of the valve seat member 23, to prevent rotation of the seat member with respect to the housing, and a retaining nut 26 is provided to lock the member 23 in place. Said nut forming part of the outer wall of housing 10 and further adapted to serve as alignment means for the punching device, as hereinafter described. A valve assembly is carried by the valve seat member 23, and this assembly may comprise a valve ball 27 adapted to mate with a valve seat 28 in the inwardly directed face of the member 23, and a suitable guide cage 29 is provided to guide the valve ball 27 between the positions indicated in full and dot-

dash lines in Fig. 9, as more particularly described hereinafter.

The mechanical puncher assembly may comprise a cylinder 30 provided with a forward head member 31 adapted to engage the outer wall of the housing 10 as defined by the rearward face 26a of the nut 26, a rearward head member 32, and a reciprocating piston rod 34, the forward end of the piston rod extending through the forward head member 31 and terminating in a coupling 35 adapted to receive a punch rod 36 to normally dispose said punch rod within the tuyère pipe 19. Projecting forwardly from the forward head member 31 we provide a ball support sleeve 37 adapted to engage the valve ball 27 when the puncher assembly is attached to the housing 10, and to hold said ball out of engagement with the reciprocating piston rod. The forward end of the head member 31 is preferably recessed as at 38 to receive the support sleeve 37, and the member 37 may conveniently be utilized as a gland nut for a packing 39 around the piston rod 34. The head member 31 may be retained on the cylinder 30 through the agency of a retaining nut 40.

The piston member 33 is preferably provided with forward and rearward piston skirts 41a and 41b having packing means such as oppositely directed cup seals 33a and adapted to define oppositely directed compression spaces 42a and 42b at the respective sides of the piston. Coatingly shaped projections are provided as at 43 and 44 on the respective rearward and forward ends of the head members 31 and 32, to enter the respective compression spaces 42a and 42b, said compression spaces being adapted to prevent the piston from hammering against the head member at the respective forward and rearward ends of the reciprocating stroke of the piston member while providing both a rapid deceleration of the reciprocating assembly and a rapid acceleration in the opposite direction.

The puncher assembly is retained in place upon a housing 10 through the agency of an adjustable ball type clamp, the rearward end of the rearward head member 32 being recessed as at 45 to slidably receive a jack screw nut 46 which is longitudinally grooved as at 47 to receive a dog point set screw 48 threadedly located in the head member 32 and protected by the retaining nut 49 which holds the head member 32 in place upon the rearward end of the cylinder 30. A jack screw 46a is threadedly disposed within the jack-screw nut 46 and is provided with a hexagonal socket 46b to receive the wrench used to tighten the nut 46 against a relatively rigid cross-strap 50 of a bail 51 is pivotally mounted on the housing 10 as at 52. The cross-strap 50 is provided with an opening 50a through which the above-mentioned wrench may be extended into engagement with the socket 46b.

The puncher cylinder 30 is provided with a valve chest 53 carrying a double "D" valve 54 having separate "D" valves 54a and 54b. Inlet ports 55 and exhaust ports 56 are provided, together with a common intake and exhaust port 57 at each end of the cylinder 30 which are alternatively connected to the inlet and exhaust ports governed by the movement of the double "D" valve under the influence of an operating yoke 58 connected to a valve actuating rod 59 pivotally connected to an operating or control handle 60 pivotally mounted on the valve chest head 61. A packing 62 is preferably provided for the rod 59, together with a gland nut 63. A high pressure inlet 64 is

provided to the chest 53, which communicates with the flexible connection 14 through a connector 14a.

When a puncher 15 is to be attached to a housing 10, the ball valve 27 will be in the full line position of Fig. 9, and as the puncher is attached to the housing, the forward end or enlarged tip 36a of the punch rod is passed into the opening 22 in the valve seat member 23 into contact with the ball 27. The puncher is then pressed forwardly, lifting the ball 27 from its seat 28 against the blowing-air pressure, and the punch rod is then passed into the tuyère pipe 19. When the support sleeve 37 surrounding the piston rod 34 is passed through the hole 22 into contact with the ball 27 this ball will be supported in the dot-dash position of Fig. 9, out of contact with the rod 34. The forward face of the head member 31 is then brought against the rearward face of the retaining nut 26 to align the puncher relative to the housing 10 and the associated tuyère opening as defined by the tuyère pipe 19, and to seat thereupon and prevent egress of air from the space 21 to the atmosphere. The usual pressure in the blowing air line will not ordinarily exceed about 12 to 15 p. s. i., wherefore an adequate seal may readily be had between the mating flat faces of the nut 26 and the head member 31. The rearward face of the nut 26 may be provided with a conical guiding seat 66 and the rearward end of the support sleeve may be enlarged to form a male seat member 67 coaxially shaped with respect to the seat 66 to assist in positioning the puncher 15 centrally of the hole 22, so that the punch rod 36 will be substantially centered within the tuyère pipe 19 as well as axially aligned therewith. When the puncher 15 is in place upon the housing 10, the bail clamp 50-51 may be swung upwardly to cause the cross-strap 50 to be positioned behind the jack screw 46a, and the jack screw tightened through the above-mentioned wrench, which will force the nut 46 outwardly against the cross-strap and force the puncher firmly against the housing. A shoulder 50b may be provided along the lower edge of the cross-strap 50 to engage the lower edge of the retaining nut 49 and facilitate the rapid placement of the bail clamp with respect to the puncher, if desired.

During operation of a converter in the production of "blister" copper, the puncher assembly 15 will be attached to a housing 10 after the manner shown in Fig. 3, with the punch rod 36 extending through the tuyère pipe 19 towards the discharge end 19a of the pipe 19. In the normal position of the valve-actuating handle 60 the air pressure from the air chest 53 is applied to the forward side of the piston 33, the double "D" valve assembly 54 being in the position of Fig. 3 and the inlet port 55 at the forward end of the cylinder 30 being uncovered. The continued supply of high pressure air in this manner would cause the piston 33 to be moved to the position of Fig. 5. With the piston in the position of Fig. 5, the forward end of the punch rod 36a will be located at a withdrawn or rearward position such as shown in dot-dash lines at 36a'. When the handle 60 is moved forwardly, the double "D" valve assembly 54 is moved forwardly and the valve portion 54a connects the cylinder inlet port 55 at the forward end of cylinder 30 to the adjacent exhaust passage 56, and the valve portion 54b uncovers the inlet port 55 at the rearward end of the cylinder 30 and allows the air from the chest 53 to enter the cylinder 30 at the rearward end. This air is admitted rearwardly of the piston packing or cup seal 33a, and

sufficient clearance is allowed between the skirt 41b and the cylinder 30 to allow the air to pass rearwardly of the skirt to force the piston forwardly. Relatively high pressure air is employed to operate the puncher 15, compared with the low-pressure air supplied for blowing purposes, and we have found that air at a gauge pressure in the neighborhood of 70 p. s. i. or more is satisfactory.

As the piston 33, the piston rod 34 and the punch rod 36 are driven forwardly, toward the position indicated in dot-dash lines at 36a' in Fig. 3, the skirt 41a will cover the cylinder port 55 at the forward end of the cylinder 30, defining a compression zone between the area 42a within the skirt 41a and the inwardly projecting portion 43 of the cylinder head member 31. The pressure build-up within this space will cause a rapid deceleration of the piston 33 and the elements connected thereto, preventing forcible impact against the cylinder head member 31, and will cause the projecting end 36a of the punch rod 36 to quickly reverse its direction of movement. The chest pressure acting upon the valve operating rod 59 will normally aid said rod to assume the position of Fig. 5, so it is merely necessary for the operator to press the handle 60 forwardly momentarily, and then immediately reverse his pressure, so that the valve assembly is returned by the chest air pressure and the pull of the operator's hand, to the position of Fig. 5. The release of pressure at the rearward side of the piston 33 upon movement of the double "D" valve to the position of Fig. 5, taken with the admission of pressure to the forward side of the piston, produces a rapid acceleration of the piston and the parts carried thereby and the punch rod tip is therefore rapidly withdrawn from the molten charge. It has been found that the operator soon judges the length of time to maintain pressure upon the handle 60 to effect an almost instantaneous reversal of the stroke of the piston 33. As the result of motion studies on the puncher action, it has been found that satisfactory reversal of the piston assembly is obtained as long as the pressure on the valve handle 60 is reversed somewhere near the end of the piston stroke, the precise timing not being critical, but the more rapid the reversal the better.

The timing of the release of the valve handle 60 does have an effect upon the length of time the projecting tip 36a of the punch rod remains within the molten charge, which normally varies from a maximum of about $\frac{1}{5}$ second to as little as $\frac{1}{75}$ of a second.

The punching device is adapted to provide a rapid acceleration of the punch rod tip along the tuyère tube until the position of an accretion or obstruction is reached, and preferably to a position slightly forward of the inner end of the tuyère opening, wherefore a maximum velocity is obtained for the purpose of shearing through or breaking away such accretion or obstruction. This maximum velocity is preferably then quickly reduced by a rapid deceleration of the punch rod assembly so as to permit a quick reversal of the motion of such punch rod without deleterious impact upon the cylinder head member at the forward end of the stroke. A rapid acceleration in the rearward stroke of the punch rod assembly is also desired, so that the enlarged tip portion of the punch rod may be pulled back through the restriction 71a without danger of sticking. The air cushion provided between the piston 33 and the cylinder head member 31 assists materially in stimulating this rapid development of high

velocity in the return stroke. It will be observed that the piston cup seals 33a are so located with respect to the ports 55 in the cylinder 30 that these cup seals are not required to pass over the ports, and are consequently protected against undue wear. The projecting skirt portions 41a and 41b serve to cut off the ports 55 at the forward and rearward stroke positions of the piston, and the acceleration of the piston from either the forward or rearward full stroke positions, as well as the deceleration of the piston at the ends of the strokes, will be a function of the amount of clearance provided between the piston skirts 41a-41b and the side wall of the cylinder 30. The less this clearance is, the greater the deceleration from the air cushion at each end of the stroke; the more this clearance is, the greater the acceleration away from such end positions, both the deceleration and the acceleration being controlled by the air flow between the respective compression spaces 42a and 42b and the ports 55, past the piston skirt portions, under any given inertia value for the reciprocable punch rod assembly.

In order to secure optimum punching results, independent of the skill of the operator in judging the most effective instant for returning the handle 60 to effect the outward punch rod stroke, we may provide automatic means for effecting a reversal of the operation of the mechanical punching device. Such an embodiment is illustrated in Figs. 10-15, and referring thereto: a puncher cylinder is indicated at 70, corresponding to the cylinder 30, above, provided with forward and rearward head members 71 and 72, and a reciprocable rod assembly including a piston member 73 and a piston rod 74 adapted to carry a punch rod at its forwardly projecting end, after the manner of the piston rod 34, above. A ball-support sleeve 75 is preferably provided, mounted on the head 72, together with packing means 76 for the rod 74.

A valve chest or air chamber 77, provided with a pressure air inlet 77a is mounted upon the cylinder 70, within which a slide valve 78 carrying forward and rearward "D" valve members 79 and 80 cooperating with inlet ports 81 in the cylinder wall 30 and outlet ports 82 communicating with ports 81 and adapted to be placed in communication with the port 81 at the respective ends of the cylinder in the valve position shown for the member 79. A valve actuating stem 84 is provided, extending through packing 85 in the head member 86 at the rearward end of valve chest 77, and adapted to be engaged by a valve-actuating handle or lever 87 provided with forked side arms 87a pivotally mounted as at 88 on a guide bracket 89 and adapted for movement between the full line position of Fig. 10 to the dot-dash position 102.

Interiorly of the chamber 77 we provide a differential cylinder 90 having an enlarged bore portion 90a and a reduced bore portion 90b, within which a differential piston member 91 is disposed, said piston having an enlarged portion 91a disposed within the bore portion 90a and a reduced portion 91b disposed within the bore portion 90b. The piston member 91 is provided with a piston rod 91' adapted to engage the forward end 84a of the valve actuating stem 84. A pressure passage 92 is provided to establish communication between the bore 90a and the interior of the cylinder 70 rearwardly of the piston 73 when said piston approaches its forward stroke position, as through a valve control tube 93 mounted on the

rearward head member 72 and provided with ports 93a adapted to be uncovered by the piston 73. The control tube 93 extends through a bore 94 in the piston 93 thence through a bore 95 in the piston rod 14. Some clearance is preferably provided at the bore 94 so that pressure from the bore portion 90a may be dissipated into the cylinder 70 and thence outwardly through ports 81, 82 and passage 93 even though the ports 93a are covered by the piston 73. A venting opening is provided as at 96 to connect the cylinder bore 90a rearwardly of the piston portion 91a to the atmosphere, to facilitate free movement of the differential piston 91 as hereinafter described.

The form of mechanical punching device shown in Figs. 10 through 15 is adapted to cause forward movement of the piston 73, piston rod 74 and the thereto-connected punch rod upon movement of the handle 87 from the dot-dash position 102 towards the full-line position of Fig. 10, with the return action of the piston assembly being effected independent of the position of the handle 87. For this purpose, we provide means whereby the handle 87 may be caused to engage and operate the valve 78 to the forward stroke operating position, and then disengage the valve stem so as to become independent thereof until such operative engagement is re-established manually. Such means may be attained by providing opposed flats 97 on the rearwardly projecting end of the stem 84, against which the forked side arms 87a of the handle 87 may bear; a pair of opposed notches 98 are provided in the flats 97, in position to be engaged by opposed pins 99 mounted on the forked side arms 87a and biased toward the notches 98 through springs 100 retained by cap means 101.

In Fig. 13 we have illustrated the relative positions of the handle means and the valve stem prior to the start of a punching operation, in which the position of the handle 87 would be that shown at 102. The valve stem 84 would be in an extreme left hand position, with the extreme left end 103 of the valve stem in engagement with the inner edge 104 of the guide bracket 89. The pins 99 are thus in engagement with the notches 98. The differential piston member 91 would be in an extreme righthand position, with the piston rod 91' in engagement with an abutment 105 on the forward wall 106 of the chamber 77, as a result of the valve chamber air pressure against the small piston 91b. Upon forward pressure being applied to the handle 87, the pins 99 will cause the valve stem to be moved forwardly to the position shown in Fig. 10. This opens the passage 81 at the left hand end of the cylinder 70 by movement of the double "D" valve 78 to the position of Fig. 10, allowing the chest pressure to be imposed upon the piston 73, moving it forwardly, or to the right. When the limit of the forward travel of the valve stem 84 has been reached, by engagement of the end 84a with the piston rod 91', continued forward pressure on the handle 87 will cause the pins 99 to slip out of the notches 98, and the arms 87a will ride forward until they hit the rearward face of the head 87. This position is shown in Fig. 14.

When the piston 73 reaches a forward position such as to uncover the ports 93a, the cylinder pressure will be communicated to the cylinder portion 90a of the differential cylinder 90, and when the pressure at 90 builds up sufficiently to overcome the chest pressure on the piston portion 91b, the differential piston member 91 will be moved to the left, pushing the valve stem 84

with it, and moving the outer end of the valve stem to the relation shown in Fig. 15. This movement moves the double "D" valve 78 to the left, opening the passage 81 at the right end of cylinder 70 to the chest 77 and connecting the passage 81 at the left end with exhaust port 82 and passage 83. The piston skirt 73a will by that time have passed the port 81 at the right end of the cylinder, and the piston travel will be decelerated by the pressure build-up between the piston and the forward head member 11 as described above in connection with the first form of the invention. Some clearance between the skirt 73a and the cylinder wall will be provided, as described above, and the pressure applied at 81 will be communicated to the forward face of the piston 73 and the return action instituted. The pressure drop in the rearward end of the cylinder will cause a pressure drop in the cylinder portion 90a, allowing the chest pressure to return the differential piston member to its right hand position. This completes a cycle of the punching operation, and a new cycle may be started after returning the handle 87 to the position represented in Fig. 13.

The operation of a converter in the production of "blister" copper requires that the converter be rotated to various angular positions for the different phases of the converter cycle. In Fig. 2 the converter is shown in what may be termed a "normal" blowing position, in which the tuyère pipes or openings are submerged to a desired operating depth. As the blowing is continued, and slag is skimmed off from the molten charge, the size of the charge will lessen, requiring the converter to be rotated counterclockwise, for example, to a position such that the puncher mechanism occupies a position as shown in dot-dash lines at 15A. When it is desired to charge matte, flux or the like to the interior of the converter, it is customary to rotate the converter clockwise to such position, for example, as that shown at 15B for the puncher assembly, or an even further clockwise position may be required when pouring slag or the like from the opening 7; a dumping position for the converter is shown by the dot-dash position 15C for the puncher assembly, constituting an even further clockwise rotation of the converter.

Inasmuch as no time must be lost between the blowing periods, and by reason of the fact that blowing air must be supplied whenever the inner ends of the tuyère openings are submerged within the molten charge, it will be appreciated that the puncher assemblies should be maintained in fully operative condition at all positions of the converter, so that the punch rods may be operated when required at all times during which blowing air is supplied to the tuyères. The puncher assemblies are for this reason caused to be carried by the side wall or shell of the converter, and are of such over-all dimensions in a radial direction as not to materially exceed the radial dimensions of the converter, as defined by the riding rings 2. Such a requirement enforces the utilization of a punch rod operating mechanism providing a rather short operating stroke as compared to hitherto-proposed forms of mechanically operating puncher devices. This short operating stroke is adequate for the punching operation as long as the proper positioning of the inner end of the punch rod is secured. This proper positioning is preferably such as to limit the extent of penetration of the rod tip 36a into the molten charge; we have determined that a

penetration of from about 3" to 4½" is satisfactory. This proper positioning is obtained according to our invention by providing punch rods 36 of a proper length, so when attached to the piston rod 34 as at 35 the proper over-all length is secured. Inasmuch as the refractory lining 6 is subject to fluxing away during the blowing periods of the converter operation, for example, at the beginning of a converting campaign, with a new refractory lining in place around the tuyère pipes, the refractory lining is usually about 22 inches in thickness. This lining gradually erodes or fluxes away as the campaign proceeds. At the end of a campaign, usually several months later, this lining may be only 6 inches in thickness. The proper positioning of the punch rod tip as a result of this variation in lining thickness is adjusted by attaching shorter and shorter punch rods 36 to the piston rod 34.

The provision of a high-velocity inward and outward movement of the punch rod tip past the obstruction zone at the end 19a of the tuyère pipe 19 serves to cleanly remove the obstruction, and this motion, taken with the rapid withdrawal of the tip from the molten charge, results in proper maintenance of the desired flow of blowing air through the tuyères with a minimum deterioration of the punch rods. We have found that a punch rod velocity of approximately 20 ft. per second at the time the punch rod tip cuts through the accretion or obstruction is required in order to secure the desired shearing action upon the incrustation. Velocities lower than about 20'/sec. seem to result in a mere pushing of the accretion away from the tuyère opening, often breaking away relatively large areas of the lining material from adjacent the tuyère opening and seriously damaging the lining. With the high speed punching operation, the accretion is sheared through cleanly, and without damage to the interior lining.

The rapid withdrawal of the punch rod tip from the molten charge, both from the standpoint of the short duration of submergence of the tip in the charge and the high velocity attained by the tip as it reaches the obstruction zone on the return stroke, attains the desired punching operation without unduly heating the punch rod and without coating the rod tip with molten material. The tip end of the punch rod does not become deformed or become blunted, as is the case with hand-operated punch rods, but retains its relatively sharp shearing edge for an indefinite period. Actual operations have been carried out in which the punch rod was in use for hundreds of punching strokes without deterioration or accumulation of molten material on the rod. In contrast to this, a hand-operated punch rod will require cleaning after punching each "round" of tuyères (i. e., with three men to a converter, and each man attending to 15 tuyères, the rod requires cleaning after punching about 15 tuyères); not infrequently, however, a hand punch rod will stick in a tuyère opening the first time it is used, requiring its removal with "dogs" and sledges, and that punch rod will then require cleaning and usually will require re-working at its tip portion, before it may again be used.

In addition to providing the above-mentioned rapid forward and rearward punching strokes, the mechanical punching device is also preferably so arranged as to cause the projecting end of the punch rod to exhibit a pronounced "whipping" action in the punching stroke.

This "whipping" action may be obtained in

any number of ways, as will be apparent to one skilled in mechanics, and we have caused the whipping action to be established by providing an eccentric disposition of the mass of the puncher 15 with respect to the axis of operation (reciprocation) of the punch rod 36. Referring to Figs. 3 and 4 it will be visualized that the mass of the cylinder 30 and the valve chest 53 is asymmetrically disposed with respect to the axis of movement of the rod 36, and this results in a whipping of the rod tip portion 36a in a generally vertical plane. Amplitude observations made on the structure of Fig. 4, provided with an operating stroke of approximately 12½ inches, showed an amplitude averaging about 1.1" in a vertical plane and about 0.2" in a horizontal plane, measured at the inward position of the punch rod tip. The strap attachment 51 also provides some flexibility in the mounting of the puncher 15 on the adapter 10, contributing in part to the amplitude of the whipping action. It has been found, for example, that a more rigid mounting of the puncher 15 on the adapter 10 causes a reduction in the amplitude of the whipping action. In the specific arrangement shown, the whipping movement is mainly vertical; an equally useful horizontal whipping action is obtainable by mounting the member 15 with the valve chamber 53 disposed laterally to one side of the cylinder 30 instead of vertically above such cylinder.

This "whipping" action is further effective during the outward or withdrawal stroke, in that the rapidly vibrating end portion of the punch rod has to be withdrawn through the accretion zone at the tuyère discharge, which results in a battering action of the rod upon the accretion and a consequent enlargement of the tuyère opening. The material forming the accretion will ordinarily be somewhat malleable at the temperatures which exist, so that the battering delivered by the vibrating punch rod tip is productive of an appreciable enlargement. By actual observation, the openings are found to be larger than the punch rod tip diameter, and the openings in tuyères punched with our mechanical punching device are found always to be larger than the openings formed by hand-punching, using the same diameter punch rod tip in both cases.

In order to provide ample space for the whipping action of the rod tip portion, the tuyère tube 19 is preferably made of somewhat larger diameter than the diameter of the rod tip, and inasmuch as the major portion of the whipping action takes place when the rod tip is located inwardly, as at position 36a' in Fig. 3, the reduced diameter of the rod 36 forwardly of the tip portion 36a permits a wide amplitude of vibratory movement to take place. The object of the whipping action is to effect an enlargement of the tuyère discharge opening at 11a to a maximum amount, limited only by the diameter of the tuyère tube 19, so that the maximum amount of air can be introduced to the molten charge through the tuyère discharge, it being appreciated that the production capacity of a copper converter is directly related to the volume of oxidizing air which can be introduced.

Numerous modifications of the punching apparatus of this invention will occur to those skilled in the art. For example, the substitution of electromagnetic motive force for the fluid-operated punch rod reciprocating means will immediately occur to one contemplating a departure from our specific showing. For this and other obvious reasons, we do not consider our invention to be

limited to the precise details of construction herein delineated and described, but rather to the scope of the subjoined claims.

We claim:

1. In an apparatus for punching a tuyère of a rotatable converter, the combination which comprises: a housing member adapted to be secured to the shell of such a converter adjacent a tuyère opening therein, and provided with an air supply inlet, an aperture aligned with said tuyère opening and spaced therefrom, valve seat means for said aperture, and a movable valve member located within said housing member and movable into and out of position to engage said valve seat means in the space between said aperture and said tuyère opening, to prevent egress of air through said aperture; and power means detachably secured to and supported by said housing member at the position of said aperture and provided with a reciprocable rod member extending axially through said aperture into said tuyère opening, said power means being adapted to engage said valve member to hold the same away from said valve seat means and out of contact with said reciprocable rod member when said power means is attached to said housing.

2. In an apparatus for punching a tuyère of a rotatable converter having a shell, a tuyère, and an air supply housing attached to said shell and connected to said tuyère, the combination which comprises: an integral punching unit adapted for attachment to and for support substantially wholly by said housing and carrying a punch rod adapted to be disposed within said tuyère, said punching unit being provided with means supporting said punch rod independent of said housing for free reciprocatory movement therewith.

3. In an apparatus for punching a tuyère of a rotatable converter having a shell, a refractory lining, a tuyère extending through said shell and refractory lining into the interior of said converter and terminating at an obstruction zone at the inner end of said tuyère, the combination which comprises: a punching tool mounted on said converter at the position of said tuyère and including a punch rod extending within said tuyère, said punch rod being normally disposed in such position that the inner end thereof is located outwardly of said obstruction zone, said punching tool including means for reciprocating said punch rod from said normal position to a second position inwardly of said obstruction zone and back to said normal position under conditions such that the velocity of movement of said punch rod is quickly accelerated to pass through said obstruction zone at a high velocity on its inward stroke and to then quickly decelerate said punch rod as it is moved to said second position, and to quickly reverse the direction of movement of said punch rod and accelerate the return velocity thereof to pass through said obstruction zone at a high velocity in returning to said normal position.

4. In an apparatus for punching a tuyère of a rotatable converter having a shell, a tubular air inlet member defining a tuyère, and an air supply housing attached to said shell and connected to said tuyère, the combination which comprises: an integral punching unit adapted for attachment to said housing and carrying a punch rod adapted to be disposed within said tuyère for reciprocatory movement therewith, said punching unit being provided with means supporting said punch rod independent of said housing and said tuyère and out of contact therewith at all

reciprocatative positions thereof, and with means for causing a rapid forward movement of said punch rod towards the interior of said converter and for rapidly decelerating such inward movement toward an inward position and effect a rapid rearward movement, the mounting of said punch rod being such as to cause the end of said punch rod disposed within said tuyère to exhibit a whipping action when moved to said inward position, in response to such rapid deceleration.

5. In an apparatus for punching a tuyère of a rotatable converter having a shell, a tuyère, and an air supply housing attached to said shell and connected to said tuyère and provided with an outer wall provided with an opening alined with said tuyère, the combination which comprises: an integral punching unit adapted for attachment to said housing at said outer wall and carrying a punch rod adapted to be disposed within said tuyère for reciprocatory movement therewithin, said punching unit being provided with means engaging said outer wall of said housing about said opening in sealing relation to said outer wall to prevent egress of air from said housing when said unit is attached upon said housing, said engagement of said punching unit with the outer wall of said housing being adapted to aline said punch rod substantially axially of said tuyère, and said punching unit being provided with means supporting said punch rod independent of said housing.

6. In an apparatus for punching a tuyère of a rotatable converter having a shell, a tuyère, and an air supply housing attached to said shell and connected to said tuyère and having an outer wall provided with an opening alined with said tuyère and valve means normally positioned to close said opening, an integral punching unit adapted for attachment to said housing at the position of said opening and including a punch rod adapted to extend through said opening past said valve means into said tuyère, and further including means separate from said punch rod adapted to be positioned in engagement with said valve means to hold the same out of said normal position and out of engagement with said punch rod, and means for reciprocating said punch rod within said tuyère.

7. In an apparatus for punching a tuyère of a rotatable converter having a shell, a tuyère, and an air supply housing attached to said shell and connected to said tuyère, said air supply housing

5 having an outer wall provided with an opening alined with said tuyère, the combination which comprises: a punching tool provided with a rod projecting therefrom and adapted to extend through said opening and into said tuyère, said punching tool being provided with operating means for reciprocating said rod within said tuyère, said means including a cylinder member having a forward cylinder head, a piston rod extending through said cylinder head and connected to said rod, the forward end of said cylinder head being adapted to engage the outer wall of said housing in sealing engagement therewith when said rod is extended through said opening and into said tuyère; and means for detachably securing said tool to said housing and supporting said tool with said forward end of said cylinder head in engagement with said outer wall of said housing.

10 20 25 30 35 40 45 50

8. In an apparatus for punching a tuyère of a rotatable converter having a shell, a tubular air inlet passage member defining a tuyère, and an air supply housing attached to said shell and connected to said tuyère, the combination which comprises: an integral punching unit adapted for attachment to said housing and carrying a punch rod adapted to be disposed within said tuyère, said punching unit being provided with means supporting said punch rod independent of said housing and said tuyère for free inward and outward reciprocatory movement within said tuyère, and the mounting of such unit on said housing being such as to cause the end of said punch rod removed from said unit to undergo a whipping movement having a marked amplitude transverse to the direction of reciprocatory movement in the reversal of reciprocatory movement from inward to outward motion.
